DESIGN FOR A WALL BRACKET OR THE LIKE

Peter J. Cronen, Minneapolis, Minn.

Application May 27, 1946, Serial No. 130,108

Term of patent 7 years

(Cl. D33—3)

To all whom it may concern:

Be it known that I, Peter J. Cronen, a citizen of the United States, residing at Minneapolis, in the county of Hennepin and State of Minnesota, have invented a new, original, and ornamental Design for a Wall Bracket or the Like, of which the following is a specification, reference being had to the accompanying drawing, forming part thereof.

Fig. 1 is a front view of a wall bracket, showing my new design.

Fig. 2 is a side view thereof.

I claim:

The ornamental design for a wall bracket or the like, substantially as shown,

PETER J. CRONEN.
